US0D1025929S

(12) **United States Design Patent** (10) Patent No.: **US D1,025,929 S**
(45) Date of Patent: ** May 7, 2024

(54) **CONTROLLER FOR DIGITAL SIGNAGE**

(71) Applicant: **LG ELECTRONICS INC.**, Seoul (KR)

(72) Inventors: **Jaewon Lim**, Seoul (KR); **Seungdon Lee**, Seoul (KR)

(73) Assignee: **LG ELECTRONICS INC.**, Seoul (KR)

(**) Term: **15 Years**

(21) Appl. No.: **35/516,386**

(22) Filed: **Dec. 28, 2022**

(80) **Hague Agreement Data**

Int. Filing Date: **Dec. 28, 2022**

Int. Reg. No.: **DM/226666**

Int. Reg. Date: **Dec. 28, 2022**

Int. Reg. Pub. Date: **Feb. 24, 2023**

(30) **Foreign Application Priority Data**

Jul. 1, 2022 (KR) 30-2022-0026545
